UNITED STATES PATENT OFFICE.

SIDNEY C. ANSCHELL, OF CHICAGO, ILLINOIS, ASSIGNOR TO THE FOLLY TOWN COMPANY, A CORPORATION OF ILLINOIS.

DESIGN FOR A CARTON.

Application filed March 6, 1924. Serial No. 8,849. Term of patent 14 years.

To all whom it may concern:

Be it known that I, SIDNEY C. ANSCHELL, a citizen of the United States, residing at Chicago, in the county of Cook and State of Illinois, have invented a new, original, and ornamental Design for Cartons, of which the following is a specification, reference being had to the accompanying drawings, forming a part thereof.

In the drawings:—

Fig. 1 is a perspective view of the carton.
Fig. 2 is a side elevation from the rear of Fig. 1.

I claim:—

The ornamental design for a carton, as shown.

In testimony whereof, I have signed my name to this specification.

SIDNEY C. ANSCHELL.
